CLAIM

The ornamental design for a multi-purpose parts washer with stainless steel plate, as shown and described.

DESCRIPTION

FIG. 1 is a perspective view of the multi-purpose parts washer with stainless steel plate showing our new design;

FIG. 2 is a top plan view thereof;

FIG. 3 is a side view thereof;

FIG. 4 is a bottom plan view thereof;

FIG. 5 is an opposite side view thereof;

FIG. 6 is a front elevational view thereof; and,

FIG. 7 is a rear view thereof.

The broken line portions of the drawings are for illustrative purposes only and form no part of the claimed design.

1 Claim, 4 Drawing Sheets
